[57] CLAIM

The ornamental design for an umbrella handle with flashlight, as shown and described.

DESCRIPTION

FIG. 1 is a perspective view of an umbrella handle showing my new design;

FIG. 2 is a right side view thereof;

FIG. 3 is a left side view thereof;

FIG. 4 is a front view thereof;

FIG. 5 is a rear view thereof;

FIG. 6 is a top view thereof; and

FIG. 7 is a bottom plan view thereof.

FIG. 8 is a perspective view of an alternative embodiment of the umbrella handle design;

FIG. 9 is a right side view of the alternative embodiment;

FIG. 10 is a left side view of the alternative embodiment;

FIG. 11 is a front view of the alternative embodiment;

FIG. 12 is a rear view of the alternative embodiment;

FIG. 13 is a top view of the alternative embodiment; and,

FIG. 14 is a bottom plan view of the alternative embodiment. The strap shown broken away in FIGS. 8-14 to indicate indeterminate length.
